HARRY RINZO TSUTSUI, OF LOS ANGELES, CALIFORNIA.

TURN-TABLE.

1,268,409.

Specification of Letters Patent.

Patented June 4, 1918.

Application filed January 31, 1918. Serial No. 214,641.

To all whom it may concern:

Be it known that I, HARRY RINZO TSUTSUI, a subject of the Emperor of Japan, residing at Los Angeles, in the county of Los Angeles 5 and State of California, have invented new and useful Improvements in Turn-Tables, of which the following is a specification.

This invention relates to improvements in turn tables, particularly those designed for 10 the purpose of permitting automobiles and like vehicles to be turned within a narrow space, drive-way or within a garage.

It is one of the objects of this invention to provide a turn table of the character described which is exceptionally simple as to 15 construction and entirely automatic in operation, the weight of the vehicle serving to actuate the table so as to cause the same to turn, carrying with it the vehicle.

20 Another object of the invention is to generally improve turn tables so as to render them reliable in operation and durable, and to reduce the cost of installation and operation thereof. A further object of the invention 25 is to provide a turn table which, when supporting a vehicle or object thereon, will, under the weight of the vehicle or object, rotate and upon the removal of the vehicle or object therefrom will automatically assume 30 normal position.

The invention further consists in the novel and useful provision, formation, combination, association, inter-relation and relative arrangement of parts and members, all as 35 hereinafter described, shown in the drawings, and finally pointed out in claims.

In the drawings:

Figure 1 represents a plan view broken away in part, and in section, of a turntable 40 constructed in accordance with the present invention;

Fig. 2 represents a side elevation of the table;

Fig. 3 represents a side elevation of the 45 table in diagrammatic illustration showing the positions of a vehicle in approaching and being supported by the table; and

Fig. 4 represents an enlarged detail fragmentary vertical sectional view with parts 50 broken away so as to clearly illustrate the particular construction thereof.

Referring in detail to the drawings, A designates preferably a circular platform comprising a table, said platform or table 55 being constructed of any suitable material and having central supporting means B, also

auxiliary supporting means C. Associated with the means C is inclined supporting means D, which, in combination with means generally designated E and associated with 60 the support B for the table, provides for the automatic turning or rotation of the table as will be later more fully described.

In installing the table the ground, pavement or floor in which the table is to be installed is cut away to a suitable depth that will allow the table to be disposed substantially flush with the said surface, and there may be provided a suitable base member 1 in the bottom of said cut-away portion. 65 Mounted upon the base 1 is an upstanding tubular member 2 having a flange 3 upon its lower end, through which flange fastening elements 4 are inserted to secure the member 2 to the base. A vertical shaft or axle 5 is 70 rigidly secured to the center of the platform or table A and is rotatably mounted in the tubular member 2.

The means B C D and E coöperate to produce rotative movement of the table automatically when the weight of the object to be turned is placed upon the table. The means E comprises pins 6 and 7 which are secured one above the other to the shaft 5 at a point midway the ends thereof and are 85 located in planes one above the other upon opposite sides of said shaft. There are provided oppositely directed and inclined or spiral slots 8 and 9 in the tubular member 2, each slot embracing substantially half the 90 circumference of the member 2, and the pins 6 and 7 extend through and engage in the slots 8 and 9, respectively. These pins are preferably provided with heads 10 and may be removably mounted in the shaft so as to 95 provide for their renewal in case of wear or breakage thereof. The member 2 is considerably longer than the shaft 5 and there may be provided suitable bearing members 11 to provide for free rotation of the shaft 5 100 within the member 2. There is provided means for returning the table to normal position and which acts to prevent too rapid rotation of the table. This means consists of counter-weights 12 which are secured to 105 the outer ends of levers 13. The levers 13 are pivoted intermediate their ends as at 14 to upstanding bearings 15 which are secured as at 16 to the base 1, on opposite sides of the tubular member 2. The inner ends of 110 the levers are disposed at a point spaced from the member 2 and pivotally connected

as at 17 with a link 18, the latter being inserted through vertically opposed slots 19 formed in the member 2. The shaft 5 engages and rests upon the link 18, which latter follows the movement of the shaft during the operation of the device.

The means C for preventing wabbling of the table and for assisting the means E in rotating the table, comprises depending supporting members 20 and 21 which are each secured as at 22 to the under side of the table and upon their lower ends carry flanged rollers 23. These rollers 23 rest upon circular rails 24 and 25 of the inclined supporting means D. The rails 24 and 25 are mounted upon a stepped base member 26, the rail 24 being above the one 25 and inclined in an opposite direction thereto. These rails 24 and 25 correspond in inclination and pitch to the slots 8 and 9 in the member 2. The rollers 23 of the members 20 coöperate with the inner rail 24, whereas the rollers 23 of the supports 21 coöperate with the outer rail 25. There may be provided friction rolls 27 which are journaled upon vertical pins 28 carried by the supports 20 and 21. These rolls 27 are positioned to extend below the treads of the rails 24 and 25 and to engage the outer sides of the tread portions of such rails, as shown in Fig. 4 of the drawings. Preferably there are provided six of the supports 20 and 21, three of the supports 20 being mounted upon the rail 24 and the remaining three supports 21 co-
operating with the rail 25. Inasmuch as these rails 24 and 25 are arranged as to inclination or pitch in correspondence with the inclination or pitch of the slots 8 and 9 in the member 2, the weight of the vehicle or object supported upon the table will act jointly upon the means E and C to produce rotation of the table. There may be provided a man hole 29 in the table A. This man hole is preferably located to one side of the center of the table and is of such size to permit of the passage of a person therethrough in order to repair or inspect the parts located beneath the table.

In the operation of the turn table, assuming that the same is in position for operation, the surface of the table is located at this time a distance, for example, of an inch and a half above the surface of the floor or roadway. The automobile or other vehicle to be turned by the table is driven over and upon the table so that the weight thereof rests solely upon the turn table. The weight of the vehicle upon the table will cause the pins 6 and 7 to traverse the slots 8 and 9 riding upon the walls of said slots, and this downward movement of the pins in a spiral path produces rotation of the table. As the pins 6 and 7 descend or begin to traverse the slots, the rollers 23 of the supports 20 and 21 upon the rails 24 and 25 will move in cor-

respondence with the pins 6 and 7 and likewise produce rotative movement of the table. As the shaft 5 descends during the rotation of the table, it depresses and moves downwardly the link 18. This action likewise depresses the inner ends of the levers 13 and lifts the weights 12. The table A is designed to make one half turn and after having made this turn the surface thereof is disposed substantially an inch and a half below the surface of the floor or road in which the table operates. In this connection it will be noted that the extent of movement of the table downwardly is three inches and that during such movement downwardly it makes a complete half turn. However, these dimensions may be varied at will and if desired the table may be made to turn a greater or less distance and have a greater or less drop by the construction and arrangement of the slots 8 and 9, together with the means C. After the vehicle upon the table has been turned it may be driven off from the table and upon relieving the table of the weight of the vehicle the weights 12 with their associated mechanism act to return the table to normal position. As the weights 12 descend the inner ends of the levers 13 and link 18 are raised within the slots 19 and this raising of the link 18 produces a lifting action upon the shaft 5 causing the same to be raised and turned while so moved, with the result that the table A is turned again into normal position. This action may be repeated as often as desired and it will be seen that as the mechanism is comparatively simple there will be little likelihood of breakage or extreme wear upon the parts thereof. The shaft 5 is caused to rotate in the member 2 when moved upwardly or downwardly by the pins 6 and 7 which operate within the spiral slots 8 and 9. This action is also accentuated by the rollers 23 riding upon the rails 24 and 25, the latter being inclined in correspondence to the pitch of the slots 8 and 9. The weights 12 prevent too rapid rotation of the table and serve to immediately return the table to a normal position upon removal of the weight of the vehicle from the table. The slight projection of the table above the surface of the roadway or floor will not in any way interfere with the driving of a vehicle or the placing or rolling of a vehicle upon the table, and likewise the position of the table after the vehicle has been turned thereby, at a point below the surface of the floor or roadway, will not interfere with the movement of the vehicle from off the table.

It will be seen that I have provided an extremely reliable and simply constructed turn table which may be installed and operated at a comparatively low cost and which will operate entirely automatically, it only being necessary to drive or move the

vehicle upon the table, allow the vehicle to remain upon the table until the latter has turned, and then remove the vehicle from the table, the return of the table to normal position taking place automatically.

5 While I have illustrated and described the preferred embodiment of my invention I do not wish to be limited thereto, and it is to be understood that I may make minor changes as to details of construction, size and proportion of parts, as required, without departing from the true spirit and scope of the invention as disclosed.

10 Having thus disclosed my invention, I claim and desire to secure by Letters Patent:

1. In improvements of the character disclosed, a revolute platform, a central shaft depending from said platform, a tubular upright bearing slidably and revolutely receiving the shaft, said bearing having a spirally-arranged slot therein, a member carried by said shaft and engaging in said slot, means for returning the shaft and table to normal position, rollers connected with the table adjacent the periphery thereof, and a runway upon which said rollers engage, said runway having a pitch corresponding to that of the slot in the tubular bearing.

20 2. In improvements of the character disclosed, a revolute table, a shaft secured to and depending from the center of said table, an upright bearing slidably and revolutely receiving the shaft, said tubular bearing having oppositely arranged spiral slots therein, members fixed to the shaft and engaged in said slots, means for returning the shaft and table to normal position, rollers connected with the table adjacent to the periphery thereof, and oppositely inclined rails upon which said rollers ride, said rails being inclined in correspondence to the pitch of the slots.

25 3. In improvements of the character disclosed, a revolute table, a shaft secured to and depending from the center of said table, an upright bearing slidably and revolutely receiving the shaft, said tubular bearing having oppositely arranged spiral slots 30 therein, members fixed to the shaft and en-

gaged in said slots, means for returning the shaft and table to normal position, rollers connected with the table adjacent to the periphery thereof, oppositely inclined rails upon which said rollers ride, said rails being inclined in correspondence to the pitch of the slots, said means for returning the table and shaft to normal position comprising a link vertically slidably mounted with in the tubular bearing and engaged with the lower end of the shaft, levers pivoted intermediate their ends and disposed upon opposite sides of the tubular bearing, said levers having their inner ends connected with the link, and weights secured to the outer ends of the levers.

35 4. In improvements of the character disclosed, a revolute platform, means centrally supporting said table and which acts under the weight of a load placed upon the table to rotate the table, means coöperating with the last named means to return the table to normal position, and further means supporting the table adjacent to the periphery thereof and which acts under the weight 40 of a load upon the table to cause rotation of the table.

5. In improvements of the character disclosed, a revolute platform, means centrally supporting said table and which acts 45 under the weight of a load placed upon the table to rotate the table, means coöperating with the last named means to return the table to normal position, and further means supporting the table adjacent to the periphery thereof and which acts under the weight 50 of a load upon the table to cause rotation of the table; said further means comprising supports depending from the table, rollers carried upon the supports, and independent 55 rails upon which the rollers ride, said rails being inclined in opposite directions.

In testimony whereof, I have signed my name to this specification in the presence of two subscribing witnesses.

HARRY RINZO TSUTSUI.
